G. Bruce Talbert Attorney

UNITED STATES PATENT OFFICE.

CHARLES W. RUSSELL, OF SIOUX FALLS, SOUTH DAKOTA.

HOOP-ROLLER.

1,348,745.

Specification of Letters Patent.

Patented Aug. 3, 1920.

Application filed November 21, 1918. Serial No. 263,545.

To all whom it may concern:

Be it known that I, CHARLES W. RUSSELL, a citizen of the United States, residing at Sioux Falls, in the county of Minnehaha 5 and State of South Dakota, have invented new and useful Improvements in Hoop-Rollers, of which the following is a specification.

This invention comprehends generally improvements in that class of inventions 10 known as games and toys and more particularly relates to a hoop roller.

It is the principal aim and object of this invention to provide a device of the above 15 mentioned character for rolling and guiding a hoop as by batting it, the construction being novel and enabling the child or user to allow the hoop to roll freely or else to be engaged and retained under control, as 20 desired.

More particularly the present invention consists in the provision of a device of the above mentioned character designed from a single piece of wire bent to form a handle 25 and shank and designed at the outer end to form a curved batting arm and a retaining trundling ring.

Among the other aims and objects of this invention may be recited the provision of 30 a device of the character described with a view to compactness, and in which the number of parts are few, the construction simple, the cost of production low and the efficiency high.

Other improvements and novel details in the construction and arrangement of the various parts of the apparatus will be brought out more in detail in the description to follow which for a clear understanding 40 of the invention should be considered in connection with the accompanying drawings forming a part hereof, and wherein is disclosed for the purpose of illustration a convenient and satisfactory embodiment of the 45 invention. It is to be noted in this connection that minor changes in the construction and arrangement of parts may be made without departing from the principle of operation of the various parts.

The invention is clearly illustrated in the accompanying drawings, in which:

Figure 1 is a perspective detail showing one manner of using the device in conjunction with the hoop.

Fig. 2 is a perspective detail showing an-

other manner of using the device in conjunction with the hoop; and

Fig. 3 is an end elevational detail of the device.

Similar characters of reference are employed in all of the above described views, 60 to indicate corresponding parts.

Referring now, more particularly, to the accompanying drawings there is illustrated a hoop 1 actuated by means of the improved 65 rolling device generally designated by the numeral 2.

In reducing the present invention to practice this rolling device is formed from a single piece of substantial resilient wire 70 bent upon itself intermediate its ends to form a handle ring 3 while the side portions are twisted together to provide a relatively stiff shank 4. The terminal of one side portion of the wire is extended at substantially right angles to the longitudinal axis 75 of the shank and is slightly curved to provide a batting arm 5. The terminal of the other side portion is extended in an opposite direction from the batting arm 5 and is bent 80 to provide a resilient ring 6 of a substantially open type, the free terminal portion of the ring being slightly offset from the common plane of the shank and the arm, lying over but positioned in spaced relation 85 to the shank to provide a substantial guide 7 for facilitating the application of the ring about the hoop 1 when it is desired to use the ring in the nature of a retainer and guide as well as a bat for the hoop. 90

In use, to connect the device to the hoop as shown in Fig. 1 it is only necessary to arrange the shank against the hoop and manipulate the handle so that the shank will be moved from the hoop at the same time 95 care being taken to hold the shank against the hoop so that the hoop will pass beneath the guide 7 and be engaged by the ring 6. The child or user now holds the handle ring and shank in one hand and uses the device 100 in the nature of a bat so that the forward movement may be imparted to the hoop, and of course as the ring is engaged about the hoop the latter is retained under control and at the same time is readily guided. As 105 shown in Fig. 2 the ring has been disengaged from the hoop while the handle has been manipulated so that the batting arm may be swung to engage the hoop with a view of rolling it. The curved formation of the 110

batting arm enables the user to guide the hoop while striking the hoop with the arm.

It is believed in view of the foregoing description that a further detailed description 5 of the invention is entirely unnecessary. Likewise it is believed that the advantages of the invention will be readily apparent.

As many changes could be made in the above construction and many apparently 10 widely different embodiments of this invention could be made without departing from the scope thereof it is intended that all matter contained in the above description or shown in the accompanying drawings 15 shall be interpreted as illustrative and not in a limited sense. It is also to be understood that the language used in the following claims is intended to cover all the generic and specific features of the invention herein described and all statements of the 20 scope of the invention which as a matter of language might be said to fall therebetween.

What is claimed is:

1. A device of the character described 25 formed from a single piece of metal bent to

provide a handle ring, a twisted shank continuing from the handle ring, a curved batting arm projecting at right angles from the longitudinal axis of the shank, and a resilient open ring formed at the end of the 30 shank and projecting in a direction opposite the arm.

2. A device of the character described formed from a single piece of wire bent intermediate its ends to form a handle ring, 35 the side portions continuing therefrom being twisted together to provide a relatively stiff shank, the terminal of one side portion being curved and arranged at substantially right angles to the longitudinal axis of the 40 shank to provide a batting arm, the terminal of the other side portion being extended in an opposite direction and designed to form an open ring, and the extreme free terminal of the last mentioned 45 ring portion being offset and lapped over but spaced from the outer end of the shank to form a guide.

In testimony whereof I affix my signature.
CHARLES W. RUSSELL.
